[57] CLAIM

The ornamental design for a toy puzzle, as shown and described.

DESCRIPTION

FIG. 1 is a perspective view of a toy puzzle showing our new design;

FIG. 2 is a top plan view thereof showing on a slightly enlarged scale;

FIG. 3 is a bottom plan view thereof;

FIG. 4 is a right side elevational view thereof;

FIG. 5 is a left side elevational view thereof;

FIG. 6 is an end elevational view thereof;

FIG. 7 is an end elevational view thereof of the end opposite that shown in FIG. 6;

FIG. 8 is a perspective view thereof shown on a slightly reduced scale with the puzzle pieces in an exploded condition;

FIG. 9 is a perspective view of a modified embodiment of the design shown in FIGS. 1 through 8;

FIG. 10 is a top plan view thereof shown on a slightly enlarged scale;

FIG. 11 is a bottom plan view thereof;

FIG. 12 is a right side elevational view thereof;

FIG. 13 is a left side elevational view thereof;

FIG. 14 is an end elevational view thereof;

FIG. 15 is an end elevational view of the end opposite that shown in FIG. 14;

FIG. 16 is a perspective view thereof shown on a slightly reduced scale with the puzzle pieces in an exploded condition;

FIG. 17 is a top perspective view of a second modified embodiment of the design shown in FIGS. 1 through 8;

FIG. 18 is a top plan view thereof shown on a slightly enlarged scale;

FIG. 19 is a bottom plan view thereof;

FIG. 20 is a right side elevational view thereof;

FIG. 21 is a left side elevational view thereof;

FIG. 22 is an end elevational view thereof;

FIG. 23 is an end elevational view of the end opposite that shown in FIG. 22; and,

FIG. 24 is a perspective view thereof shown on a slightly reduced scale with the puzzle pieces in an exploded condition.
